UNITED STATES PATENT OFFICE

166,505

HYDRAULIC POCKET SLASHER

Edwin W. Smith, Dallas, Tex.

Application June 4, 1951, Serial No. 15,389

Term of patent 14 years

(Cl. D55—1)

To all whom it may concern:

Be it known that I, Edwin W. Smith, a citizen of the United States of America, residing at Dallas, in the county of Dallas and State of Texas, have invented a new, original, and ornamental Design for a Hydraulic Pocket Slasher, of which the following is a specification, reference being had to the accompanying drawing, forming a part hereof.

Figure 1 is a perspective view of a hydraulic pocket slasher, showing my new design.

Figure 2 is a top plan view of Figure 1 on a reduced scale.

Figure 3 is a rear perspective view of the hydraulic pocket slasher.

The essential features of my design reside in the portions shown in full lines.

I claim:

The ornamental design for a hydraulic pocket slasher, substantially as shown and described.

EDWIN W. SMITH.
